ATTORNEY

UNITED STATES PATENT OFFICE.

ERWIN R. STOEKLE, OF MILWAUKEE, WISCONSIN, ASSIGNOR TO THE CUTLER-HAMMER MFG. CO., OF MILWAUKEE, WISCONSIN, A CORPORATION OF WISCONSIN.

PROTECTIVE DEVICE FOR ELECTRIC CIRCUITS.

Application filed February 20, 1922. Serial No. 537,860.

To all whom it may concern:

Be it known that I, ERWIN R. STOEKLE, a citizen of the United States, residing at Milwaukee, in the county of Milwaukee and

5 State of Wisconsin, have invented new and useful Improvements in Protective Devices for Electric Circuits, of which the following is a full, clear, concise, and exact description, reference being had to the accompanying drawing, forming a part of this specification.

This invention relates to protective devices for electric circuits, and more particularly to such devices involving in their 15 action vaporization of a conductor which is liquid at working temperatures.

In my Patent No. 1,499,420, dated July 1, 1924, is disclosed and claimed such a type 20 of protective device having certain features in common with that herein contemplated.

In the construction and operation of such devices, particularly those designed to require voluntary resetting following operation thereof, great difficulty has heretofore 25 been experienced in providing for effecting such resetting readily and positively without sacrificing some necessary or desirable operative characteristic of the device, and the present invention has as an object that 30 of overcoming such difficulty.

Another object is that of providing such a device adapted, following operation thereof, to maintain the controlled circuit positively interrupted pending voluntary resetting and also to enable accomplishment 35 of such resetting action with ease and certainty.

Another object is that of simplifying and improving generally the construction and 40 operation of such devices.

Other objects and advantages will hereinafter appear.

In the accompanying drawing,—

Figure 1 is a vertical sectional view of a 45 form of the apparatus embodying the invention, certain circuit connections being illustrated diagrammatically; while,

Fig. 2 is a diagrammatic view including 50 modified circuit connections adapting the device to a slightly different character of control.

Referring to Fig. 1 of the drawing, the same illustrates a thermally responsive over-load circuit interrupter requiring voluntary 55 resetting and comprising an insulating and

heat absorbent support 5, which may be similar to and standard with the corresponding element of my patent aforesaid, said support having a heating coil 6 associated therewith and being internally 60 provided with a longitudinal passage 7.

A thermally responsive circuit control element is carried within said passage 7 and within the heating coil 6 substantially as illustrated. Said element comprises a tube 65 8 of glass, or other suitable insulating material, closed at its lower end and outwardly flared at its upper end substantially as illustrated, said tube being of relatively large internal diameter and being preferably internally 70 unconstricted. A conductor 9 is sealed within the lower end of the tube and connected with an electrode 10 located within the tube and extending upwardly within the space surrounded by the coil 6.

A reciprocable plunger 11, of conductive material, is arranged within the upper portion of the tube 8 and spaced upwardly above the electrode 10 substantially as illustrated, said plunger having a bore 12 extending from the bottom thereof to a point considerably above the upper end of the tube 8 when the plunger is assembled, and said bore having at its upper end one or more openings leading outside said plunger. 85

Said plunger is furthermore provided with an enlargement 13 located substantially as illustrated and preferably provided with a downwardly tapered conical surface substantially conforming to the contour of the 90 adjacent flared portion of the tube 8 and being adapted to coact therewith in the manner of a valve with its seat, suitable packing 14 of asbestos or other material being preferably interposed for purposes 95 hereinafter set forth.

A conductive cap 16 is cemented or otherwise permanently secured upon and about the upper end of the tube 8 in a manner to provide a chamber 17 in communication 100 with the interior of said tube and also with the bore 12 substantially as illustrated. Said cap 16 is provided with an axial opening through which the upper portion of the plunger 11 is adapted to extend, making therewith a sliding fit.

The upper end of the enlarged portion of said plunger is preferably provided with an upwardly facing annular shoulder 18, whereas a helical spring 19 is compressed 110

between said shoulder and the adjacent portions of the cap 16 and serves under normal conditions to maintain the plunger in its lowermost position with the valve in engagement with its co-operating seat.

The space within the tube 8 not occupied by the aforescribed parts is filled with a conductive medium, indicated at 20, which is liquid at working temperatures, such for example as metallic mercury, said conductor being adapted to extend slightly above the upper portion of the tube and within the aforescribed recess 17. However, the free surface 21 of such conductor is to be maintained under all conditions below the level of the passages connecting the bore 12 with such recess. The stem of the plunger 11 is provided exteriorly of the cap 16 with an insulating knob or operating handle 22.

The circuit to be controlled is caused to include the liquid conductor 20 aforesaid as by connecting one side of the circuit through terminal 23 which is connected with spring clip 24 and thence to conductor 9. The opposite side of the circuit is connected through terminal 25 and spring clip 26 to the cap 16 as illustrated. The heating coil 6 is connected in the circuit in accordance with an electrical condition of which it is desired that the aforesaid circuit be controlled. Obviously the foregoing circuits may be the same or may be distinct.

In the operation of the device, so long as the current in the coil circuit does not exceed a given value, the heat evolved by said coil is absorbed and dissipated by the support with sufficient rapidity to prevent operation of the device for interrupting circuit. However, upon a given value of brief overload or upon a lesser value of more prolonged overload, the heating effect of said coil is sufficient to effect vaporization of an intermediate portion of the liquid conductor located between the two electrodes aforesaid whereupon the portion of said conductor located above such vaporized portion is expelled with great rapidity upwardly through the bore 12 into the recess 17 of cap 16, thereby suddenly interrupting the controlled circuit between fluid contacts, automatic re-establishment of said circuit being prevented due to the aforesaid fact that the upper end of the external openings of said bore 12 are located above the level which the conductive liquid within the recess can attain, the valve 13 serving also to prevent reflux of the liquid.

If now the plunger 11 be lifted by means of the knob 22 against the force of spring 19, the valve is opened, permitting ready and copious reflux of liquid within the tube by means of the annular space between said tube and plunger, such passage being independent of the bore 12, whereby any gaseous or vaporous matter located within the tube

is readily displaced by the inflowing liquid with the result that such reflux of the latter is facilitated and expedited. Obviously such reflux of the liquid serves to reset the device which is thus rendered again active for completing the circuit subject to subsequent re-interruption upon the occurrence of overload.

It is of course to be understood that in general the diameter of the bore 12 will be materially less than that of the individual bubbles of vapor of the liquid which form due to heating by the coil 6, thereby preventing free boiling of the liquid conductor and providing substantially explosive action for circuit interruption as aforesaid. Thus the size of said bore best adapted to provide the foregoing effects is ordinarily too small to permit resetting of the device by reflux of conductive liquid through the same passage with the facility and certainty herein required. However, provision of the aforesaid enlarged reflux passage provides amply for such resetting. Moreover, provision of the valve 13 normally closing said reflux passage and also the aforesaid arrangement whereby the upper end of the bore 12 is at all times above the free surface of the conductive liquid within chamber 17 provides for positively preventing resetting of the device except by opening of said valve.

With the circuit arrangement illustrated in Fig. 1, the heating coil 6 is connected in the circuit of a motor 27 which is to be protected, the joint circuit of the motor and coil being controllable by means of an electro-responsive switch 28 having a closing coil 29 connected across the motor circuit through the circuit interrupting element aforesaid and also preferably through a suitable control switch 30 as illustrated.

Thus said heating coil is subjected to influence of the motor current for determining response of the circuit interrupting element, whereas in responding said element serves to open the energizing coil of switch 28 which thereupon opens and interrupts the common circuit of the motor and the heating coil. Obviously restarting may be thereafter effected by simply closing the switch 30, assuming the same to have been opened, following resetting of the circuit interrupting element in the manner aforesaid.

It is of course to be understood that wherever desirable or necessary the heater coil may be connected in series with the circuit interrupting element and with the translating device to be protected substantially as illustrated in Fig. 2, the circuit connections there illustrated being obvious.

What I claim as new and desire to secure by Letters Patent is:

1. A circuit interrupter comprising a conductor which is liquid at working tempera-

- tures, electro-thermic means including an external heater for subjecting said conductor to fluid pressure of its own vapor to effect sudden interruption of circuit through said conductor and means requiring operation thereof to effect restoration of circuit.
2. A circuit interrupter comprising a conductor which is liquid at working temperatures, electro-thermic means including an external heater for effecting sudden interruption of circuit through said conductor, and means, including a voluntarily operable valve, requiring operation thereof to effect restoration of circuit.
- 15 3. A circuit interrupter comprising a conductor which is liquid at working temperatures, a support for said conductor providing for connection thereof in the circuit to be protected, electro-thermic means for subjecting said conductor to fluid pressure of its own vapor for interruption of circuit therethrough and means requiring voluntary actuation thereof to effect restoration of circuit, said latter means including a passage 20 for influx of said liquid within said support and a valve to control said passage.
4. A circuit interrupter comprising a conductor which is liquid at working temperatures, a support for said conductor providing for connection thereof in the circuit to be protected, electro-responsive means for subjecting said conductor to fluid pressure of its own vapor for effecting displacement of liquid of said conductor, subject to an inverse time element, for rendering the latter electrically discontinuous, means providing against automatic restoration of continuity of said conductor and voluntarily operable means providing for replacement of a like 35 quantity of liquid for restoring continuity of said conductor, said support and said latter means having associated parts providing different passages for such displacement and replacement of the liquid respectively.
5. In a protective device for electric circuits, the combination with a tubular insulating support, of a conductor which is liquid at working temperatures to be carried by said support, means for subjecting said conductor to fluid pressure of its own vapor to cause sudden efflux of liquid of said conductor from said support for rendering the conductor electrically discontinuous, a member extending within said support providing a passage for such efflux of liquid and to prevent automatic reflux thereof and means for moving said member relatively
- to said support for permitting reflux of liquid for restoring continuity of said conductor.
6. In a protective device for electric circuits, the combination with a tubular insulating support arranged vertically and having a flared upper end providing a valve seat, of a tubular electrode extending downwardly in said support, a conductor which is liquid at working temperatures to be contained in said support, means for subjecting said conductor to fluid pressure of its own vapor to cause a sudden upward flow of liquid of said conductor through said electrode for rendering said conductor electrically discontinuous, said electrode having parts to prevent return of liquid therethrough and being spaced from the interior of said tube to provide for return flow of liquid, a valve associated with said electrode to coact with said seat for controlling such return flow of liquid, means tending to maintain said valve closed and means providing for voluntary opening of the valve.
7. In a protective device for electric circuits, the combination with an insulating and heat absorbent base and a tubular electric heating element associated therewith, of a thermally responsive circuit interrupting element insertable within said base and said heating element for support by the former in a vertical position, said element comprising an insulating tube having an electrode sealed within its lower end for exterior circuit connection, a terminal clip for said electrode carried by said base for positioning said tube therein, a tubular electrode 85 penetrating the upper end of said tube, a conductive cap sealed about the upper end of said tube and electrically connected with said upper electrode, a conductor which is liquid at working temperatures carried within said tube in contact with said electrodes, said heating element and said base providing for subjection of said conductor to fluid pressure of its own vapor to cause sudden expulsion of liquid from said tube for rendering the conductor electrically discontinuous subject to an inverse time element, said upper electrode and said tube having parts providing against automatic reflux of the expelled liquid and voluntarily operable means 90 associated with said upper electrode to provide for reflux of such liquid within said tube.
- 105 In witness whereof, I have hereunto subscribed my name.

ERWIN R. STOEKLE.
